ARTICLE EJECTING DEVICE FOR WRAPPING MACHINES

Fred Farmer and Helmer Andersen, Brooklyn, N. Y., assignors to American Machine & Foundry Company, a corporation of New Jersey

Application May 2, 1934, Serial No. 723,588

9 Claims. (Cl. 93—2)

This invention relates to an improvement in wrapping machines wherein the wrapped packages are delivered into a drying or sealing chamber from which they are expelled by the forward pressure of the following packages delivered into the chamber.

The main object of the invention is to provide means for automatically ejecting all the packages from the sealing chamber or runway at the end 10 of a run, or at any other cessation of the feed during which there are no advancing packages to push out the packages remaining in the sealing chamber.

In wrapping machines of the type specified, the sealing chamber has heretofore been provided with an automatic trip mechanism, said mechanism comprising a contact finger which was released when a break in the regular continuity of the package arrival occurred. This contact, when 20 so released, closed an electric circuit to a solenoid, thereby energizing the latter which thereupon actuated suitable mechanism for moving a cam rail into the path of the empty package pushing means, and thus causing the latter to engage and 25 propel the last package of the continuous series through the sealing chamber onto a delivery conveyor.

The above described unit worked satisfactorily but due to its complex design and the costly price 30 of manufacture, a much simpler device, as disclosed in the present invention, has been needed.

In the present invention, a trip mechanism is provided which automatically releases a latch when a break in the regular continuity of the 35 package arrival occurs, such as by the missing of one or more packages, or at the end of a run. The latch when released permits a cam rail to move into the guide path of the empty package pushing means and thus causes the latter to engage 40 and push the last package of the continuous series until it is deposited on the delivery conveyor. The cam rail remains in this position until the next package travels over and depresses a raised plate which is provided in the base of the sealing chamber. This plate when depressed, raises a cam reset arm which pulls back the aforesaid cam rail thereby restoring the same to its non-operative position. With these and other 45 objects not specifically mentioned in view, the invention consists in certain constructions and combinations hereinafter fully described and then 50 specifically set forth in the claims hereunto appended.

In the accompanying drawing which forms a 55 part of this specification and in which like char-

acters of reference indicate the same or like parts:

Fig. 1 is a partial plan view of a wrapping machine showing the improved mechanism for automatically ejecting the packages; and

Fig. 2 is a side elevation of the same.

In carrying the invention into effect there is provided a heat sealing runway, a continuous series of pushers, mechanism for moving said pushers into and through part of the length of the runway to advance a continuous series of packages 10 into the runway, automatic mechanical means normally operative to cause said pushers to continue their travel through the remainder of the runway, a package-controlled feeler for incapacitating said means, and a stop normally operative 15 to incapacitate said means and periodically actuated by said mechanism to release said means, so that all the packages in the runway will be cleared out when a break occurs in the continuity of the packages being advanced by the pushers. 20 In the best constructions contemplated said mechanism includes an endless traveling chain on which the pushers are pivotally mounted, operating arms rigidly connected to the pushers, and rollers on the operating arms, and said means includes a cam rail alongside the runway and movable 25 into position to engage the rollers on the operating arms and maintain the pushers in upright package-engaging position throughout the length of the runway, and said stop being arranged to 30 obstruct the movement of the cam rail into operative position and adapted to be raised out of obstructing position by said mechanism. These various means and parts may be widely varied in construction for the particular device selected to 35 illustrate the invention is but one of many possible concrete embodiments of the same. The invention, therefore, is not to be restricted to the specific construction shown and described.

Referring to the drawing, the pusher fingers 5, 40 clamped in pairs on shafts 6 loosely mounted in bearing lugs 7 attached at equal intervals to endless conveyor chains 8, convey the packages P to the sealing runway or chamber of the packaging machine. The chains 8 run over the rear idler 45 sprockets 9 mounted on shaft 10 and over a pair of front drive sprockets, not shown. The shaft 10 is carried by brackets 11 attached to a cross member 12 held by the side frames 13.

The packages P pass over a table 14, which 50 forms the bottom of the sealing runway, and the adjustable sealer plates 15 form its sides. The pairs of pushers 5 are spaced apart considerably more than the width of the packages P and are lifted out of engagement with the latter within 55

the entrance to the sealing chamber, which is long enough to accommodate a row of packages at a time so that no package is ejected from the sealing chamber until the packages have filled the chamber and a new package is entering.

Operating arms 16 attached to the cross shafts 6 of conveyor chains 8 support rollers 17 which guide the pusher fingers 5 by engaging with guides and rails during their travel with the 10 conveyor chains. The rollers 17 of the pusher fingers 5 on the lower run of the conveyor chains travel along the bottom of a stationary guide rail 18, thereby maintaining the pusher fingers in upright position to engage and push the package 15 into the sealing runway. Guide rail 18 carries an adjustable end piece 19 terminating in a curved portion 20 with which the rollers 17 of each pair of pusher fingers engage successively when the package advanced by them has entered 20 the sealing chamber, whereby the pusher fingers are swung up over the package during the continued travel of the conveyor chains, leaving it stationary until the next package is pushed against it. The end piece 19 is secured adjustably 25 to rail 18 so that the point of disengagement of the pusher fingers may be set in accordance with the width of the package to be wrapped by the machine. The lower runs of chains 8 are supported by rails 21 to prevent their sagging which, 30 if excessive, would interfere with the proper action of the pusher fingers.

The table 14 is provided with an opening 22 large enough to allow free vertical motion of a cup 23 projecting therethrough. A teat at the 35 upper end of cup 23 is riveted to a feeler plate 24 which may be formed of any suitable resilient material such as steel. The free end of the plate 24 normally assumes the raised position 24' indicated by dotted lines in Fig. 2, and its other 40 end is bent back over the front edge of the table 14 and secured thereto. One end of a depressor finger 25 is loosely inserted into the bowl of cup 23, and its other end is fastened to a clamp block 26 fast on the shaft 27. The shaft 27 is free to 45 turn on trunnions 28 projecting from the support bars 29 fastened to the tie rod 30 connecting the side frames 13.

An arm 31 clamped to shaft 27 is pinned to a connecting rod 32 the upper end of which is attached to a reset lever 33. One end of lever 33 is 50 fulcrumed on a stud 34 carried by an angle 35 fastened on the cross bar 12. The other end of lever 33 is forked, the prongs 36 and 37 thereof embracing a reset angle 38 secured to arm 42. A 55 bracket 39 fastened to the cross bar 12 carries a set of studs 40 on which are pivoted the arms 41 and 42 which carry a cam rail 43. The projecting prong 44 of the forked end of lever 33 abuts the cam rail 43.

When the pusher fingers 5 deliver a package to the table 14, the package is pushed over the feeler which is in its raised position 24' shown in dotted lines. The weight of the package depresses the feeler with the finger 25, thus, with the aid of an 60 adjustably mounted balance weight 45 mounted on the finger 25, counteracting the downward pressure of the reset linkage and raising the rod 32 to lift the prong 36 of the lever 33 into engagement with the reset angle 38. The engagement of said prong with the angle 38 swings the 65 cam rail 43 into its non-operative position, thereby allowing the roller 17 of fingers 5 to follow the curved guide surface 20 of the end piece 19 and permit the fingers 5 to clear the package P after 70 it has reached a position beyond the feeler 24, 75

thus leaving the package P and any previously delivered packages in the sealing chamber unless the latter has been filled, in which case the foremost package in the chamber is ejected during the delivery of the package P to the chamber.

During the travel of the pusher fingers 5, a pin 46 protruding from the guide rail 18 is periodically lifted against the leaf spring 47 by the rollers 17. The lifting of pin 46 raises a stop 48 attached to the free end of the spring 47 out of the position in which it normally obstructs the movement of the cam rail 43 into operative position. While the stop 48 is in raised position, any failure of the pushers 5 to deliver a package onto plate 24 permits the latter to remain in its raised position 24' and the lever 33 to swing down about its fulcrum, causing the top prong 37 to engage the reset angle 38 and thus move cam rail 43 from its non-operative position into alignment with the guide rail 18 behind the end piece 19 of the latter. 20 The cam rail 43 now forms a continuation of the straight rail 18 so that the roller 17 of the empty pair of fingers 5 is now guided along cam rail 43, thus engaging with the package P left by the preceding finger and pushing the same, together 25 with previously delivered packages P' still in the sealing chamber, onto the delivery conveyor 49.

What is claimed is:

1. In a wrapping machine, the combination with a heat sealing runway adapted to receive 30 a row of packages and heat seal the same, of a continuous series of pushers, mechanism for moving said pushers into and through part of the length of said runway to advance a continuous series of packages into said runway, automatic 35 mechanical means normally operative to cause said pushers to continue their travel through the remainder of the length of said runway and thus clear the runway of packages, a feeler arranged in said runway to engage the packages being delivered thereto by said pushers and be actuated thereby to incapacitate said means, and a stop normally operative to incapacitate said means and periodically actuated by said mechanism to release said means, whereby all the packages in 45 said runway will be cleared out of the runway when a break occurs in the continuity of the series of packages being advanced by said pushers.

2. In a wrapping machine, the combination with a heat sealing runway adapted to receive 50 a row of packages and heat seal the same, of a continuous series of pushers, mechanism for moving said pushers into and through part of the length of said runway to advance a continuous series of packages into said runway, automatic 55 mechanical means normally operative to cause said pushers to continue their travel through the remainder of the length of said runway and thus clear the runway of packages, a feeler arranged in said runway to engage the packages being delivered thereto by said pushers and be actuated thereby to incapacitate said means, and a stop normally operative to incapacitate said means and periodically actuated by said mechanism to release said means, whereby all the packages in 60 said runway will be cleared out of the runway when a break occurs in the continuity of the series of packages being advanced by said pushers, said mechanism including an endless traveling chain on which said pushers are pivotally mounted, arms rigidly connected to said pushers, rollers on said arms, a stationary guide rail arranged to engage the rollers on said arms and thereby hold said pushers in upright package-engaging position, and an end piece carried by said guide rail 70 75

and overhanging said runway, the end piece being arranged to engage the rollers on said arms and shaped to permit said arms and pushers to swing upwardly while the pushers are advancing 5 packages along said runway so that the pushers may disengage the packages.

3. In a wrapping machine, the combination with a heat sealing runway adapted to receive a row of packages and heat seal the same, of a continuous series of pushers, mechanism for moving said pushers into and through part of the length of said runway to advance a continuous series of packages into said runway, automatic mechanical means normally operative to cause said pushers to continue their travel through the remainder of the length of said runway and thus clear the runway of packages, a feeler arranged in said runway to engage the packages being delivered thereto by said pushers and be actuated thereby to incapacitate said means, and a stop normally operative to incapacitate said means and periodically actuated by said mechanism to release said means, whereby all the packages in said runway will be cleared out of the runway 15 when a break occurs in the continuity of the series of packages being advanced by said pushers, said mechanism including an endless traveling chain on which said pushers are pivotally mounted, operating arms rigidly connected to said 20 pushers and rollers on said operating arms, and said means including a cam rail alongside said runway, pivoted arms carrying said cam rail, and a lever adapted to swing said pivoted arms to move the cam rail into position to engage the 25 rollers on said operating arms and thereby maintain the pushers in upright package-engaging position throughout the length of the runway, and said feeler being mounted in said runway 30 to be depressed by a package pushed thereover and connected to said lever to swing said cam rail out of operative position when it is depressed by a package.

4. In a wrapping machine, the combination with a heat sealing runway adapted to receive a row of packages and heat seal the same, of a continuous series of pushers, mechanism for moving said pushers into and through part of the length of said runway to advance a continuous series of packages into said runway automatic 40 mechanical means normally operative to cause said pushers to continue their travel through the remainder of the length of said runway and thus clear the runway of packages, a feeler arranged in said runway to engage the packages being delivered thereto by said pushers and be actuated thereby to incapacitate said means, and a stop normally operative to incapacitate said means and periodically actuated by said mechanism to release said means, whereby all the packages in said runway will be cleared out of the runway 45 when a break occurs in the continuity of the series of packages being advanced by said pushers, said mechanism including an endless traveling chain on which said pushers are pivotally mounted, operating arms rigidly connected to said 50 pushers, rollers on said operating arms, and a stationary guide rail arranged to engage the rollers on said operating arms and thereby hold said pushers in upright-package-engaging position, and said means including a cam rail alongside said runway and swingable into position to engage the rollers on said operating arms and thereby maintain the pushers in upright package-engaging position throughout the length of the runway, and said stop being arranged to obstruct the movement of said cam rail into operative position and adapted to be raised out of obstructing position by said mechanism.

5. In a wrapping machine, the combination with a heat sealing runway adapted to receive

a row of packages and heat seal the same, of a continuous series of pushers, mechanism for moving said pushers into and through part of the length of said runway to advance a continuous series of packages into said runway, automatic mechanical means normally operative to cause said pushers to continue their travel through the remainder of the length of said runway and thus clear the runway of packages, a feeler arranged in said runway to engage the packages being delivered thereto by said pushers and be actuated thereby to incapacitate said means, and a stop normally operative to incapacitate said means and periodically actuated by said mechanism to release said means, whereby all the packages in said runway will be cleared out of the runway when a break occurs in the continuity of the series of packages being advanced by said pushers, said mechanism including an endless traveling chain on which said pushers are pivotally mounted, operating arms rigidly connected to said pushers, and rollers on said operating arms, and said means including a cam rail alongside said runway, pivoted arms carrying said cam rail, and a lever adapted to swing said pivoted arms to move the cam rail into position to engage the rollers on said operating arms and thereby maintain the pushers in upright package-engaging position throughout the length of the runway, and said feeler being mounted in said runway to be depressed by a package pushed thereover and connected to said lever to swing said cam rail out of operative position when it is depressed by a package.

6. The combination with a heat sealing runway adapted to receive a row of packages and heat seal the same, of a continuous series of pushers, mechanism for moving said pushers into and through part of the length of said runway to advance a continuous series of packages into said runway, automatic mechanical means normally operative to cause said pushers to continue their travel through the remainder of the length of said runway and thus clear the runway of packages, and a feeler connected to said means and arranged in said runway to engage the packages being delivered thereto and be actuated thereby to incapacitate said means.

7. The combination with a heat sealing runway adapted to receive a row of packages and heat seal the same, of a continuous series of pushers, mechanism for moving said pushers into and through part of the length of said runway to advance a continuous series of packages into said runway, automatic mechanical means normally operative to cause said pushers to continue their travel through the remainder of the length of said runway and thus clear the runway of packages, and a feeler connected to said means and arranged in said runway to engage the packages being delivered thereto and be actuated thereby to incapacitate said means, said mechanism including an endless traveling chain on which said pushers are pivotally mounted, operating arms rigidly connected to said pushers, and rollers on said operating arms, and said means including a cam rail alongside said runway, pivoted arms carrying said cam rail, and a lever adapted to swing said pivoted arms to move the cam rail into position to engage the rollers on said operating arms and thereby maintain the pushers in upright package-engaging position throughout the length of the runway.

8. The combination with a heat sealing runway adapted to receive a row of packages and

heat seal the same, of a continuous series of pushers, mechanism for moving said pushers into and through part of the length of said runway to advance a continuous series of packages into 5 said runway, automatic mechanical means normally operative to cause said pushers to continue their travel through the remainder of the length of said runway and thus clear the runway of packages, and a stop normally operative to 10 incapacitate said means and periodically actuated by said mechanism to release said means.

9. The combination with a heat sealing runway adapted to receive a row of packages and heat seal the same, of a continuous series of 15 pushers, mechanism for moving said pushers into and through part of the length of said runway to advance a continuous series of packages into said runway, automatic mechanical means normally operative to cause said pushers to continue 20 their travel through the remainder of the length of said runway and thus clear the runway of

packages, and a stop normally operative to incapacitate said means and periodically actuated by said mechanism including an endless traveling chain on which said pushers are pivotally mounted, arms rigidly connected to said pushers, rollers on said arms, and a stationary guide rail arranged to engage the rollers on said arms and thereby hold said pushers in upright package-engaging position, and said means including a 10 cam rail alongside said runway and swingable into position to engage the rollers on said arms and thereby maintain the pushers in upright package-engaging position throughout the length of the runway, and said stop being arranged 15 to obstruct the movement of said cam rail into operative position and adapted to be raised out of obstructing position by said mechanism.
